UNITED STATES PATENT OFFICE.

JOHN C. FOWLE, JOHN P. CHRISTOPHER, AND WILL P. SMITH, OF MICHIGAMME, MICHIGAN.

MINE-RAILWAY.

SPECIFICATION forming part of Letters Patent No. 314,010, dated March 17, 1885.

Application filed January 14, 1885. (No model.)

To all whom it may concern:

Be it known that we, JOHN C. FOWLE, JOHN P. CHRISTOPHER, and WILL P. SMITH, all of Michigamme, in the county of Marquette and State of Michigan, have invented 5 a new and Improved Mine-Railway, of which the following is a full, clear, and exact description.

The object of our invention is to lessen the 10 cost of transportation of ore, coal, &c., by utilizing part of the power of the hoisting-rope for operating a surface-car.

The invention consists in a winding-drum and gearing suitable for operating it from a 15 pulley over which the hoisting-rope passes, the rope for operating the surface-car being connected with the said drum.

Reference is to be had to the accompanying drawings, forming part of this specification, in 20 which similar letters of reference indicate corresponding parts in both the figures.

Figure 1 is a longitudinal sectional elevation of a shaft-house and part of the mine, showing the arrangement of our improved 25 mine-railway. Fig. 2 is an enlarged side view of part of the gearing.

The shaft A is journaled in the shaft-house B, and on it is mounted a grooved pulley, C, over which the hoisting-cable D is passed, 30 which passes from the engine-house and extends down the inclined shaft E and is secured to the skip F, running on tracks G in the shaft E, and on the tracks G', extending upward from the shaft, and provided with a dump, H, near its upper end, at which the 35 skip F is dumped automatically.

An inclined track, J, leads from the shaft-house to a dumping-ground, or to cars, vessels, &c., or wherever the ore, coal, &c., are 40 to be deposited. On the track J the dumping-car K runs, which is secured to a cable, L, passed over an angle-pulley, I, and secured to and wound on a drum, M, journaled on a frame, T, having one end pivoted at N, 45 and having the other end connected with a lever, O, pivoted in suitable hangers and provided with a pulling-rod, P.

A grooved friction-pinion, Q, is formed on the shaft of the drum M, or on one end of 50 the drum, and is adapted to be engaged with a friction-wheel, R, rigidly mounted on the shaft A.

The operation is as follows: The skip F is pulled upward in the shaft E by the cable D,

and thereby the pulley C is revolved, over 55 which the cable D passes. The rod P is pulled down, whereby the frame T is raised, and the friction-pinion Q is brought in contact with the wheel R, and the drum M is revolved from the wheel R, the rope L is wound 60 on the drum M, and the car K is moved in the direction of the arrow a', and by the time the dumping-car K is under the dump H the skip F arrives at the dump and dumps its load into the car K. The rod P is released, 65 the frame T moves downward slightly, and the pinion Q and wheel R are disengaged, thus permitting the car K to run down the inclined track J and the cable L to unwind from the drum M. In the meantime the skip 70 F is lowered, and when it is again raised the pinion Q and the wheel R are engaged and the car K is pulled in the direction of the arrow a' again.

Having thus described our invention, what 75 we claim as new, and desire to secure by Letters Patent, is—

1. The combination, with a pulley over which a hoisting-rope is to be passed, of a drum, gearing for revolving the drum from 80 the said pulley, and of a cable or rope secured on the said drum and connected with a dumping-car, said cable being passed over the angle-pulley, substantially as herein shown and described.

2. The combination, with the pulley C, over which the hoisting-cable D is to be passed, of the wheel R on the same shaft with the pulley C, the pivoted frame T, the drum M, journaled in the same, the pinion Q, connected with the drum, the rope L, secured on the drum, and the dumping-car K, secured to the said rope L, substantially as herein shown and described.

3. The combination, with the shaft A, of 95 the pulley C and the friction-wheel R on the same, the pivoted frame T, the lever O, the drum M, and the pinion Q on the frame T, the rope L, the track J, the car K, the track G', and the dump H, substantially as herein 100 shown and described.

JOHN C. FOWLE.
JOHN P. CHRISTOPHER.
WILL P. SMITH.
